UNITED STATES PATENT OFFICE.

GUSTAV BEHM, OF CHICAGO, ILLINOIS.

DESIGN FOR A GUITAR-BODY.

SPECIFICATION forming part of Design No. 26,398, dated December 15, 1896.

Application filed July 27, 1896. Serial No. 600,718. Term of patent 3¹ years.

To all whom it may concern:

Be it known that I, GUSTAV BEHM, a citizen of the United States, residing at Chicago, in the county of Cook and State of Illinois, have 5 invented and produced a new and original Design for the Body of Guitars and Stringed Instruments of that Class, of which the following is a specification, reference being had to the accompanying drawings, of which—
10 Figure 1 is a plan view of a guitar, showing my design. Fig. 2 is an elevation of one side of the same instrument, and Fig. 3 is an elevation in cross-section on the line 3-3 of Fig. 1.

My design is applicable to guitars and instruments of that class, such as banjos, mandolins, &c., which comprise in their construction a hollow body portion or box designed to act as a sounding-board, together with an elongated neck, which is ordinarily fretted to 15 form a finger-board, and a head in which are mounted the tuning-pegs. The body portion also carries a tailpiece to which the strings are fastened, their other ends being fastened to the tuning-pegs to vary the tension and 20 consequently the pitch of the strings, which are sounded by picking.

The feature of my design consists of a body

portion or box A substantially square in outline, the neck B being attached thereto at one corner. Instead of the single central aperture opening into the casing of the box beneath the strings, which is customary in this class of instruments, there may be two apertures C in the corners adjoining the one to which its neck is attached. These apertures 30 are of the form shown, their design being formed by four intersecting circles, as clearly shown. The tailpiece D is located in its customary place, and the head-piece E has the customary contour, except that it has as an 35 ornament the head F, which in this specific instance is designed after that of Franz Liszt.

By the employment of a box of the shape shown I secure a novel and attractive design, as well as a greater and less broken surface for the sounding-board.

What I claim is—

The design for a guitar-body substantially as herein shown and described.

GUSTAV BEHM.
